UNITED STATES PATENT OFFICE.

ANDREW C. ZWARICH, OF HOMESTEAD, PENNSYLVANIA.

MOTOR.

1,237,597.

Specification of Letters Patent. Patented Aug. 21, 1917.

Application filed March 3, 1917. Serial No. 152,299.

To all whom it may concern:

Be it known that I, ANDREW C. ZWARICH, a subject of the Czar of Russia, residing at Homestead, county of Allegheny and State 5 of Pennsylvania, have invented certain new and useful Improvements in Motors, of which the following is a specification.

This invention relates to motors for driving machines or for other purposes where- 10 in found applicable, more particularly to the type of motor disclosed in Letters Patent No. 1,179,599 granted to me and that dis- closed in application filed by me October 18th, 1916, Serial No. 126,301, and has for its 15 object, besides the objects and advantages set forth in the patent and application referred to, further aims to provide means, in a manner as hereinafter set forth, to facilitate the changing of an intermittent rotor 20 motion into a continuous one, said change of such motion being the primary object of the patent and the application heretofore referred to.

Further objects of the invention are to 25 provide a motor which is simple in its construction and arrangement, strong, durable, efficient in its use, readily set up and comparatively inexpensive to manufacture.

With the foregoing and other objects in 30 view the invention consists of the novel construction, combination and arrangement of parts as hereinafter more specifically described and illustrated in the accompanying drawings, wherein is shown an embodiment 35 of the invention, but it is to be understood that changes, variations and modifications can be resorted to which come within the scope of the claim hereunto appended.

In the drawings wherein like reference 40 characters denote corresponding parts throughout the several views:

Figure 1 is a sectional elevation of a motor in accordance with this invention.

Fig. 2 is a side elevation thereof.

Fig. 3 is a side elevation of a modified 45 form of motor in accordance with this invention.

Fig. 4 is a detail of the pawl.

Referring to the drawings in detail 1 de- 50 notes a stationary shaft provided with a crank 2 intermediate its ends and which is mounted in a pair of uprights 3.

Rotatably mounted on the shaft 1, be- 55 tween the uprights 3, is a pair of lateral shafts 4, 5, which form a part of the rotor

6 and the said shafts 4, 5, are hollow through which extends the shaft 1.

The crank 2 and said shaft 1, are positioned within the rotor and the latter is formed of two sections, one of the sections 60 of the rotor consists of a plate 7 having formed integral with the inner face thereof an annular member 8 which forms the rim of the rotor. The other section consists of a plate 9 which is detachably connected with 65 the annular member 8, by securing devices 10. The rotor 6 revolves upon the stationary shaft 1.

Mounted upon the crank 2 and eccentrically disposed with respect to the rotor 6, is 70 a disk 11, having the inner ends 12, of a series of shifting elements 13, 14, 15 and 16 loosely connected therewith.

The outer ends of the shifting elements are anchored as at 17, to the inner face of 75 the annular member 8, and the said outer ends are arranged equi-distant with respect to each other. Each of said shifting elements consists of a contractible and expandable coil spring.

Fixed to one side of the rotor, is a ratchet wheel 23 and associating therewith is a pair of actuating members 24, 25, and which are connected to a lever 26. The member 24 is connected to the lever 26 as at 27 and the member 25 is connected to the lever 26 as at 28. The lever 26 has a pair of pivoted pawls 29, 30, which extend in opposite direction with respect to each other. The ratchet wheel, actuating members, lever and pawls 90 are termed a driving element and when one of said members is operated it is adapted to intermittently rotate the rotor in one direction and when the other member is actuated it is adapted to rotate the rotor in the opposite 95 direction.

The shaft 5 is provided with a pulley or gear 31 whereby the rotor can be coupled with the machine or other device and operate the same.

The shifting elements 13 to 16 are employed to set of a continuous rotary motion for the intermittent drive, that is to say when the rotor is intermittently operated by the driving element the shifting elements 105 successively expand or contract. During the contracting movement thereof it causes the rotor to revolve and this movement is had in view of the fact that the disk 11 is eccentrically disposed with respect to the rotor 110

and that the inner ends of the shifting elements are off-center.

The foregoing elements forming the motor are substantially those as illustrated in 5 Patent No. 1,179,599 granted to me.

Referring to Fig. 3 of the drawings the motor includes the following elements similar to that employed in the motor illustrated in Fig. 1 and similar reference characters 10 are employed to designate such elements and the said elements consist of the stationary shaft 1 provided with the crank 2, shifting elements 13 to 16, disk 11 mounted on the 15 crank 2 and to which the inner ends of the shifting elements 13, to 16 are loosely connected. Besides the elements referred to which are employed in the motor shown in Fig. 1, the motor illustrated in Fig. 3 includes a pair of elongated rectangular plates 20 32, 33, which are secured to opposite sides of a circular band 34 having peripheral teeth 35. The rectangular plates or carriers 32, 33, are rotatably mounted on the shaft 1 and the ends of the plates or carriers 32, 33, 25 terminate inwardly with respect to the teeth 35 of the circular band.

The shifting elements 13 to 16 have their outer ends connected to the inner face of the band 34.

30 The carrier 32 is provided with a short shaft 37 and the carrier 33 with a short shaft 38.

Fixed to one side of the carrier 4 is a driving element constructed in a manner 35 similar to that referred to with respect to the driving element employed in Fig. 1.

The foregoing elements referred to in connection with Fig. 3 are substantially similar to that form of motor illustrated in 40 my application before referred to.

The shaft 4 in Fig. 1 has peripheral teeth 40 which extend just half the circumference of said shaft 4.

The shaft 38 in Fig. 3 is provided with 45 peripheral teeth 41 which extend just half the circumference of said shaft 38.

As the means forming the subject matter of this application are employed in connection with the form of motor shown in Fig. 50 1 or the form of motor shown in Fig. 3 is of the same construction, similar reference characters to indicate the elements of said means will be employed in the several figures of the drawings. Said means or mechanism includes the teeth of the shaft 4, or 55 the teeth on the shaft 38 and the said means

or mechanism further includes a toothed quadrant 42 which is arranged at one side of the motor and which is pivoted to a support, as at 43. The teeth of the quadrant 60 42 are indicated at 44 and are adapted to mesh with teeth 40 and 41. Connected at one end, as at 45, to the quadrant 42, is a coil spring 46, the latter having its other end anchored as at 47, to a support 48.

65 Associating with the quadrant 42 is a spring controlled pawl 49 which is mounted on a post 50, the latter has its inner end fixed in a bar 51, which is slidably mounted on posts 52, 53, and upon said posts 52, 53, 70 are arranged coil springs 54.

The pawl mechanism referred to is secured to the carrier 33 or to the plates 7 and said plates or carrier has a slot 55 through which is adapted to project posts 75 50 due to the action of the spring 54. Posts 52, 53, are secured to the inner face of the plate or carrier 7 and the pawl 49 projects beyond the outer face of the said plate or carrier 7.

80 During the revolving of the rotor, in either form of motor shown, the teeth 40 and 41, will shift the toothed quadrant 42 in one direction. After the teeth 40 or 41, clear the teeth 4 of the quadrant 44 the 85 spring 46 will shift the quadrant 42 and the latter engaging the pawl 49 give an impulse to the rotor and assist the action of the shifting elements.

80 The spring controlled pawl as the rotor revolves will be compressed when it engages the quadrant and under such conditions will not interfere with the operation of the rotor.

What I claim is:—

A motor comprising a rotor, means for 95 intermittently rotating said rotor, a series of expandible and contractible elements arranged within said rotor for changing the intermittent drive of the rotor into a continuous one, and an oscillatory mechanism 100 arranged exteriorly of and operated in one direction by the rotor and further capable of engaging with the rotor after being operated thereby for assisting said elements in changing the intermittent drive of the rotor 105 into a continuous one.

In testimony whereof I affix my signature in the presence of two witnesses.

ANDREW C. ZWARICH.
